CLAIM

The ornamental design for a foldable portable device holder as shown and described.

DESCRIPTION

FIG. 1 is a perspective view of a foldable portable device holder;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Broken lines and adjacent unshaded areas illustrate portions of the foldable portable claim device holder that form no part of the claimed design.

1 Claim, 5 Drawing Sheets
